Primary Examiner — Darlington Ly(74) *Attorney, Agent, or Firm* — Miller Law Group, PLLC(57) **CLAIM**

The ornamental design for a nailer adapter for siding, as shown and described.

DESCRIPTION

FIG. 1 is a top plan view of a nailer adapter for siding showing my new design;

FIG. 2 is a bottom plan view thereof;

FIG. 3 is a rear elevational view thereof;

FIG. 4 is a front elevational view thereof;

FIG. 5 is a right side elevational view thereof;

FIG. 6 is a left side elevational view thereof;

FIG. 7 is a top, front, and left side perspective view thereof;

FIG. 8 is a bottom, rear, and right side perspective view thereof; and,

FIG. 9 is a left side elevational view thereof as shown mounted on an exemplary nailer.

The broken lines showing the nailer is provided for the purpose of illustrating environmental structure and forms no part of the claimed design.

1 Claim, 6 Drawing Sheets(56)
